TOOL

Malcolm E. Mitchell, Hollywood, and Peter E. Mortensen and Harold W. Fowler, Oakland, Calif.; said Mitchell assignor to said Mortensen and said Fowler

Original application February 2, 1935, Serial No. 4,712, which in turn is a division of application Serial No. 720,760, April 16, 1934. Divided and this application December 12, 1936, Serial No. 115,564

5 Claims. (Cl. 29—95.1)

The invention relates to means for manufacturing a part of a coupling such as used to readily attach and detach sections or extensions of fluid circuits as air pressure systems and the like.

5 More particularly the present invention relates to a tool for forming a special part of a new and improved coupling invented by ourselves. The method of constructing this coupling has been set forth and claimed in our copending application 10 Serial Number 4712 filed February 2, 1935, and the present case is a divisional application which in turn is a division of application Serial No. 720,760 filed April 16, 1934, of said copending application.

15 The coupling in the construction of which the tool of the present invention is used, is formed in a manner concealing the means of attachment of a pair of coupling sections whereby the surreptitious removal of any portion of the fluid circuits with which the coupling is used is made 20 substantially impossible without the detection by the attendant in charge of the apparatus. To accomplish this concealed means of attachment, the coupling utilizes a section having a certain 25 inside construction and it is an object of the present invention to provide a tool for making this construction possible.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a longitudinal sectional view of a 40 coupling constructed in accordance with our invention with the separate sections thereof attached.

Figure 2 is a transverse sectional view of the 45 coupling and is taken on the plane of line 2—2 of Figure 1.

Figure 3 is a side elevation shown partly in section of a tool constructed in accordance with the present invention and shown operatively associated with a tool and coupling section supporting means.

Figure 4 is a transverse sectional view of the tool and is taken substantially on the plane of the line 4—4 of Figure 3.

55 Figure 5 is a view similar to Figure 3 but show-

ing the engagement of the tool in the coupling section.

Figure 6 is an elevational view of a reamer adapted to complete the forming operation of the coupling section.

With reference to the accompanying drawing, the coupling in the formation of which the present tool is used is illustrated in Figures 1 and 2. The coupling is composed of detachable male and female sections 12 and 13 which are arranged for telescopic engagement at their ends 14 and 16 and are preferably threaded at their opposite ends 17 and 18 to facilitate the connection of the sections to a fluid line. Extending longitudinally through the sections are aligned bores 19 and 21 for conveying fluid through the coupling. Means for sealing the sections against leakage when coupled, here comprises a packing washer 22 which is mounted in the bore 21 and arranged to engage about the end 14 of the male member, the latter being preferably formed with a slight taper to afford a wedged engagement with the washer. The washer further serves with the members detached as a seat for a valve 23 which is mounted for axial movement in the bore 21 and is normally urged by a spring 24 to seat against the washer in passage closing position and is displaceable from such position only by and upon insertion of the male end 14 through the washer.

The connection between the detachable sections is of a so-called bayonet type, a plurality of bayonet slot portions 31 being formed within the bore 21 at the end 16 of the female section and a plurality of slot engaging lugs or projections 32 are formed on the interfitting end 14 of the male section. The containing of the slot 31 within the bore 21 of the female section entirely conceals the means of attachment when the sections are attached. The slots 31 extend from the open end of the bore 21 inwardly to an 40 enlargement 33 in the bore so that defined at the inner ends of the slots is an annular shoulder 37 behind which the lugs may be locked on movement of the lugs through the slots and rotated away from the inner end of the slots. Retention of the projections in this latter position is here effected by a plurality of sockets 38 formed in the shoulder and arranged to receive and interlock with the projections. Since the insertion 50 of the male section is resisted jointly by the spring 24 and the fluid flow, the resisting force will be effective to press the projections against the shoulder when the same are engaged and into the sockets with the result that a positive lock- 55

ing of the parts will be insured. As an important feature of the coupling and serving to prevent twisting of the projections from the sockets, the projections and sockets are both formed of rectangular section so that the same will squarely abut each other when engaged and no incline is available on the interengaged sides thereof for permitting a longitudinal disengaging movement incident to a forceful twisting of the projections and sockets.

In couplings previous to the one above described it has been the practice of providing bayonet guide portions such as the grooves 31 here shown by cutting longitudinal slots through the female section which slots extend completely through and to the outside of the section side walls, and to provide the offset or locking portions of the slot by merely cutting sidewise from the inner end of the slot or by drilling the sections at a portion contiguous with the inner ends of the slots. Since the operations entailed in forming these previous constructions are well known and commonly used in machine shop practice, the manufacture of the female section 25 of the coupling presented no particular difficulty. In the coupling above described, however, wherein the guide portions 31 and the sockets 38 are formed entirely within the bore 21 of the casing 25 and are completely inaccessible for forming by the usual apparatus found in the machine shops, the manufacture of the female section of the coupling has required the development of a special tool and method for its formation. The tool of the present invention has been particularly devised to provide for the formation of the bayonet slots 31 and the sockets 38.

The female section of the coupling as will be seen from Figure 1 is composed of two parts, including a main body section 25 and a hollow end plug 26 which is threaded into the casing 25 for clamping the washer 22 in position and against a retaining ring 27 which is in turn supported on an annular shoulder 51 formed in the central bore of the section 25. As will be understood, the guide slots 31, the shoulder 37, and the retaining sockets 38 are all provided in the section 25 of the coupler. It is, therefore, with this part of the coupler which the present invention is principally concerned. Preparatory to the formation of the grooves and sockets 31 and 38 in this section, the same as first drilled axially through the member from the outer end 50 thereof with a drill diameter slightly larger than the end 14 of the cooperating coupling section. The bore thus drilled is then reamed from the same end to define the shoulder 37 and the shoulder 51 and the outer end of the bore is then threaded for receipt of the external threads on the member 26.

As above mentioned, the tool of the present invention is used to form the aforesaid grooves and sockets and in brief operates to punch from the reduced bore portion of the section 25 between the shoulder 37 and the end 16, the grooves 31 while supporting the inner wall of the bore, and then to depress the sockets 38 while supporting both the side walls of the bore and the walls of the grooves 31. The tool 53, which is illustrated in detail in Figures 3, 4, and 5, comprises a cylindrical body portion 56 which is arranged to slidably engage in the bore of the female section 25 and support the side walls thereof during the punching operation and is provided on its periphery with a plurality of offset rectangular projections 54 which are ar-

ranged on the forceful movement of the tool through the bore to engage the shoulder 37 and shear from the reduced bore portion aforesaid the grooves 31. Provided also on the periphery of the body portion 53 of the tool and intermediate the projections 54 are a plurality of offset rectangular projections 55 which serve to engage the shoulder 37 and depress the sockets 38 therein after the grooves 31 have been sheared from the side walls of the bore. Preferably the sockets are formed after the formation of the grooves and to this end the projections 55 are spaced longitudinally from the projections 54 so that their operation will be retarded from that of the projections 54. It is important during the pressing of the recesses 38 due to the tremendous strain to which the metal of the coupling section is subjected, to support the side walls of the slots 31 and to hold the same against partial closing or other distortion. For this purpose the projections 54 are extended longitudinally along the body portion of the tool a distance at least equal to the length of the grooves 31 so that after the forming of these grooves the projections 54 will lie snugly therein and hold the side walls thereof against closing or other distortion due to the stress incurred by the pressing out of the sockets 38.

Preferably the tool is reduced somewhat in cross sectional area adjacent its end 70 so as to allow for a small flow of metal towards the center of the bore between the shoulder 37 and the end 16 of the section and thereby relieve somewhat the stress on the guide grooves. This reduction in size of the tool is here effected at opposite sides 71 of the tool which are flattened from adjacent the outer end 70 to the projections 54. After the pressing operation, the bore of the section is preferably reamed and the end 16 counterbored such as by means of a reamer 40 indicated in Figure 6, to remove any bur or distortion caused by the punching out of the grooves and sockets.

As indicated in Figures 3 and 5 the tool may be supported at an end 61 in an ordinary punch press 62 and the coupling section 25 positioned on the work support 63 of the press within a guard 64 for holding the section against withdrawal with the tool. It will be noted that when the tool is inserted in the section to its farthest position as illustrated in Figure 5 the free end 70 of the tool extends from the end 16 of the section for a distance substantially equal to the depth of the sockets 38 depressed by the projections 55. In this manner the projections 54 used for forming the guide slots will be passed substantially entirely through the length of the section prior to the engagement of the projections 55 with the shoulder 37. Thus, at the time the section is subjected to the stress caused by the formation of the sockets, the guide slots will be substantially entirely formed and filled and supported by the projections 55.

We claim:

1. For use in forming a coupling section having a bore therethrough with an offset portion to define a shoulder and provided with a groove opening to the bore and extending from said shoulder to an end of said section and arranged for the receipt of a projection on an associated coupling section for movement of said projection from said end to behind said shoulder and said first section being formed with a socket in said shoulder for the receipt of said projection, a tool for forming said groove and socket comprising a cylindrical body portion having a shoulder defining a bore therethrough, a plurality of offset rectangular projections on the periphery of said body portion, and a plurality of rectangular projections on the periphery of said body portion intermediate the offset projections, said offset projections being spaced longitudinally from the rectangular projections so that the latter will not engage the shoulder until the former have been sheared from the side walls of the bore.

body portion arranged to slidably engage in and support the walls of said bore, an offset on said body portion arranged on the forced movement of said tool through said bore to punch out said groove, and a second offset on said body portion spaced longitudinally from said first offset and arranged on the forced movement of said tool aforesaid to engage and impress in said shoulder said socket.

10 2. For use in forming a coupling section having a bore therethrough and formed with a shoulder extending transversely into said bore and with guide grooves extending along the wall of said bore to said shoulder and with locking recesses in 15 said shoulder, a tool for forming said grooves and recesses comprising a body portion arranged to slidably engage and support said bore side wall, a pair of offset portions on said body portion arranged on the forced movement of the tool 20 through said bore to engage said shoulder and punch out therefrom and from said side wall said grooves, and a second pair of offset portions on said body portion spaced longitudinally from said first offset portions arranged on the forced movement 25 of the tool aforesaid to engage said shoulder and depress therein said recesses.

3. For use in forming a coupling section having a bore therethrough and formed with a shoulder extending transversely into said bore and with 30 guide grooves extending along the wall of said bore to said shoulder and with locking recesses in said shoulder, a tool for forming said grooves and recesses comprising a body portion arranged to slidably engage and support said bore side wall, 35 a pair of offset portions on said body portion arranged on the forced movement of the tool through said bore to engage said shoulder and punch out therefrom and from said side wall said grooves, and a second pair of offset portions on said body portion spaced longitudinally from said first offset portions arranged on the forced movement 40 of the tool aforesaid to engage said shoulder and depress therein said recesses, said first offset portions being of a length as to lie in and support

the walls of said grooves during the forming of said recesses.

4. For use in forming a tubular coupling section having a portion of the bore thereof reduced adjacent an end thereof to define a shoulder spaced from said end, a tool for forming a longitudinal guide groove in the wall of said reduced bore portion from said shoulder to said end and for forming a locking recess in said shoulder comprising, a body portion arranged to slidably engage and support said bore side wall, an offset projection on said body portion arranged on the forced movement of the tool through said bore to engage said shoulder and punched out therefrom and from said side wall said groove, and a second offset projection on said body portion spaced longitudinally from said first projection and arranged on the forced movement of the tool aforesaid to engage said shoulder and depressed therein said recesses, said first projection being of a length substantially equal to that of said reduced bore portion so as to lie in and support the wall of said groove during the formation of said recesses.

5. For use in forming a coupling section having a bore therethrough and formed with a shoulder extending transversely into said bore and with a guide groove extending along the wall of said bore to said shoulder and with a locking recess in said shoulder, a tool for forming said groove and recess comprising a body portion arranged to slidably engage and support said bore side wall, an offset portion on said body portion arranged on the forced movement of the tool through said bore to engage said shoulder and punch out therefrom and from said side wall said groove, and a second offset portion on said body portion spaced longitudinally from said first offset portion arranged on the forced movement of the tool aforesaid to engage said shoulder and depress therein said recess.
